UNITED STATES PATENT OFFICE.

HARRISON A. SELFRIDGE, OF NEW HAVEN, CONNECTICUT.

PAPER-FOLDING MACHINE.

Application filed July 23, 1921. Serial No. 486,966.

To all whom it may concern:

Be it known that I, HARRISON A. SELFRIDGE, a citizen of the United States, residing at New Haven, in the county of New Haven and State of Connecticut, have invented a new and useful Improvement in Paper-Folding Machines; and I do hereby declare the following, when taken in connection with the accompanying drawings 10 and the characters of reference marked thereon, to be a full, clear, and exact description of the same, and which said drawings constitute part of this application, and represent, in—

15 Fig. 1 a plan view of a paper folding machine constructed in accordance with my invention.

Fig. 2 a front view of the same.

Fig. 3 a side view of the same.

20 Fig. 4 a sectional view on the line 4—4 of Figure 2, showing the slides moved upward.

Fig. 5 a similar view showing the slides moved downward.

25 Figs. 6 and 7 strips of paper folded upon the machine.

This invention relates to improvement in paper folding machines and particularly to machines for folding paper for use in connection with pleating fabric. In the more general custom of pleating fabric, a strip of heavy paper is first folded on the lines desired for the pleating of the fabric, the fabric is then laid on this paper strip and 30 pressed. It is generally customary to score the paper strips at the point where it is to be bent, but this scoring weakens the strip, and, furthermore, the scoring occupies considerable time, as it must be done with care, 35 so that the folds shall be accurate.

The object of this invention is to produce a machine by which a strip of paper may be folded either up or down, according to the character of the pleats desired, and the 40 invention consists in the construction as hereinafter described and particularly recited in the claims.

The strip of paper, to be folded, passes between a clamping-member 10 fixed at opposite sides to uprights 11 mounted upon a suitable base 12 and a corresponding movable member 13, which is guided at opposite ends by pins 14, the lower ends 15 of which are threaded for engagement with the fixed member. These pins have attached to their upper ends arms 16 and 17 connected at

their outer ends by a pin-operating handle 18, so that both pins may be simultaneously turned by the movement of the handle. The pins 14 are formed with collars 38 which bear upon the movable clamping member 13, so that, when the pins are turned in one direction, they will press the movable clamping member 13 toward the fixed clamping member 10, so as to firmly hold a strip of paper between them, or when turned in the opposite direction, the pressure of the collars 38 on the member 13 is released so that the paper strip may be advanced. The paper is fed through the gripping-members 19 between rolls 19 and 20, one of which is provided with a gear 21 meshing with a segmental rack 22 provided with an operating-handle 24, so that, by moving the handle, the rolls will be turned to feed the paper 75 between the clamping-members. A spring-pawl 25 is provided to prevent the backward movement of the rolls.

Mounted on the fixed-member 10 is a folding slide 26, the inner corner 27 of its upper end being slightly beveled and adapted to be moved above the upper edge of the fixed-member, and mounted on the movable-member 13 is a corresponding slide 28, having the inner corner 29 of its lower end 80 slightly beveled and adapted to project beyond the upper face of the fixed-member. The slide 26 is formed with a series of vertical slots 39, through which guide studs 40 extend into engagement with the clamping member 10, a collar or washer 41 being provided to guide the slide vertically. The slide 28 is also formed with a series of vertical slots 42, through which guide studs 43 extend into engagement with the clamping member 13, a collar or washer 44 being provided to guide the slide vertically. These slides are connected together at their ends by plates 30 and 31 provided with outwardly-projecting lugs 32, to which are attached 100 links 33 connected at their lower ends to levers 34, which in turn are fixed to a transverse rock-shaft 35, to which is also affixed upwardly-projecting levers 36 connected at their upper ends by a cross-bar handle 37, 105 so that, by the movement of the handle 37 backward or forward, the slides 26 and 28 will be moved up or down.

The strip of paper is passed between the feed-rolls 19 and 20 and between the clamping-members 10 and 13, so as to project beyond the outer faces thereof. When the

paper is in position, the pin-operating handle 18 will be shifted to force the clamping-member 13 downward upon the paper, against the fixed member 10. If an upward 5 bend is to be given the paper, the handle 37 will be moved rearward, which moves the slides 26 and 28 upward, causing the slide 26 to bend the paper upward, as indicated in Figure 4 of the drawings, and 10 the beveled edge prevents the paper from breaking at the bend. After this bend is made, the pin-operating handle 18 is again shifted to separate the clamping-members, and the handle 24 is turned to feed the paper 15 to the desired extent for the next bend; the paper is again clamped in position, and if the next bend is to be a downward one, as indicated in Figure 5 of the drawings, the handle 37 will be moved forward, which 20 will depress the slides and bend the paper downward, and these operations are continued until the desired strip is formed, and as indicated in Figures 6 and 7 of the drawings, these strips varying according to 25 whether the strip is to be used for side-pleating, box-pleating or accordian-pleating.

With this machine, the paper is folded on straight lines, the folds are parallel and the strip is folded without breaking the paper 30 and the operation is performed with much less time than when done by hand.

I claim:

1. A paper folding machine, comprising a fixed clamping-member, a movable clamping-member above the same, each having a horizontal clamping-face and a vertical wall, means for feeding a strip of paper between the clamping-members, a slide connected with the outer face of the vertical wall of 35 each of said clamping-members, and means for moving the said slides up or down beyond the meeting faces of said clamping-members.

2. A machine for folding paper, comprising a fixed clamping-member and a movable clamping-member, each having a horizontal clamping-face and a vertical wall, means for connecting them together, means for 40

feeding a strip of paper between the said clamping-members, folding slides movably mounted upon the outer faces of the vertical walls of the said clamping-members, the said slides connected together, and means for moving the said slides up or down beyond the meeting faces of said clamping-members.

3. A machine for folding paper comprising a fixed clamping-member and a movable clamping-member, each having a horizontal clamping-face and a vertical wall, and means including screw-pins for connecting the two members together, said pins provided at their upper ends with arms connected by a pin-operating handle, means for feeding a strip of paper between the clamping-members, a slide movably mounted upon the vertical wall of each of the said clamping-members and means for moving the said slides up or down beyond the meeting faces of said clamping-members.

4. A machine for folding paper, comprising a fixed clamping-member and a movable clamping member, each having a horizontal clamping-face and a vertical wall, means for coupling the said clamping-members together, means for feeding a strip of paper between the said clamping-members, a slide movably mounted upon the outer face of the vertical wall of each of the said clamping-members, said slides connected together at their ends, links connected with said slides, levers connected with the lower ends of said links, a rock-shaft upon which said levers are mounted and means for turning the said rock-shaft, whereby the adjacent edges of the said slides are moved beyond the horizontal faces of the said clamping-members.

In testimony whereof, I have signed this specification in the presence of two subscribing witnesses.

HARRISON A. SELFRIDGE.
